(57) CLAIM

I claim the ornamental design for a football helmet themed beverage dispenser, as shown and described.

DESCRIPTION

FIG. 1 is a left side isometric view of a football helmet themed beverage dispenser showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings is included for the purpose of illustration and form no part of the claimed design.
